UNITED STATES PATENT OFFICE

171,811

ILLUMINABLE SIGN

Milton K. Markman, Marshall, Va., and David A. Adler, Winnetka, and Orville C. Sonntag, Chicago, Ill., assignors to Sun Oil Company, Philadelphia, Pa., a corporation of New Jersey

Application August 28, 1953, Serial No. 26,622

Term of patent 14 years

(Cl. D72—1)

To all whom it may concern:

Be it known that we, Milton K. Markman, a citizen of the United States, residing in Marshall, county of Fauquier, State of Virginia; David A. Adler, a citizen of the United States, residing in Winnetka, county of Cook, State of Illinois; and Orville C. Sonntag, a citizen of the United States, residing in Chicago, county of Cook, State of Illinois, have invented a new, original, and ornamental Design for an Illuminable Sign, of which the following is a specification, reference being had to the accompanying drawing, forming part thereof.

Fig. 1 is a front elevational view of an illuminable sign, showing our new design.

Fig. 2 is a side elevational view of Fig. 1.

Fig. 3 is a top plan view of the sign.

We claim:

The ornamental design for an illuminable sign, substantially as shown.

MILTON K. MARKMAN.
DAVID A. ADLER.
ORVILLE C. SONNTAG.
